UNITED STATES PATENT OFFICE.

RUSSELL B. FULLER, OF EVANSVILLE, INDIANA.

FOLDING CRATE.

1,172,271.

Specification of Letters Patent. Patented Feb. 22, 1916.

Application filed June 14, 1915. Serial No. 34,043.

To all whom it may concern:

Be it known that I, RUSSELL B. FULLER, a citizen of the United States, residing at Evansville, county of Vanderburg, and 5 State of Indiana, have invented certain new and useful Improvements in Folding Crates, of which the following is a specification.

This invention relates to folding crates.

My object is to improve on the construction shown in the patent to Dahlstrom, No. 1,120,693, dated December 15, 1914, to the end that the construction be simplified, strengthened, rendered more secure when set up, and better adapted to withstand 15 pressures, strains and hard knocks to which crates are subjected in use.

With these, and other not specifically mentioned, objects in view but which will appear more fully hereinafter, my invention 20 entirely dispenses with the locking catch of the Dahlstrom patented construction; employs a novel top construction at the locking end thereof, and a locking slat or bar; further, an improved construction 25 at the other end of the top; still further, hinged members of improved form whereby they possess greater strength than the hinge connectors of the aforesaid patent; and finally, an improved combination of the 30 hinge connectors or members with the top of the crate.

I have set forth hereinafter and disclosed in the drawings, the preferred embodiment 35 of the invention, but I am well aware that my improvements are susceptible of modification within the spirit and scope of the invention.

In the accompanying drawings: Figure 1 is a perspective of the complete crate when 40 closed and locked; Fig. 2, a plan view; Fig. 3, a side view showing the crate collapsed; Fig. 4, a detail perspective of a cross bar or cleat; Fig. 5, a similar view of the locking bar; and Fig. 6, a perspective of one of the 45 hinge members.

The sides and ends of the crate appear at 1 and 2, the top at 3, and the bottom at 4. As shown in Fig. 3, the sides and ends are 50 hinged together to permit folding, and also for the purpose of holding the top and bottom, by the hinge and securing members 5 which differ from the hinge members of the Dahlstrom patent in that their bridging portions 6 are permanently curved or bowed laterally in relation to the legs 7. The legs 55 7 are pivotally connected to the ends and sides of the crate and the laterally bowed portion 6 extends inwardly and is adapted to secure the top and bottom in position. The bottom rests on the sides and its corners 60 are overlapped by the bowed portion 6 of the hinge members at the bottom of the crate. The bottom is thus secured against falling out and in turn, braces the sides and ends and prevents them from collapsing. 65 The bottom can, however, be removed when the crate is to be collapsed as it has no other connections with the sides and ends.

The top 3 is composed of longitudinally extending slats, one of which, preferably 70 the central one, is longer than the others and has the extension 8 so that it overlaps the end of the crate. The top also has cross-pieces 9 and 10 overlapping the sides of the 75 crate. The outer slats of the top are at one end cut away at 11 corresponding to the parts 6 of the hinge members 5 so that said hinge members at that end of the crate directly engage the ends of the slats constituting the top. 80

The means for locking the top 3 comprises a bar 12 which is adapted to be loosely positioned on the extension 8 and to have one end slipped under one of the hinge members 5 and its other end sprung under 85 the other hinge member 5 at that end of the crate. As the hinge members 5 are connected to the sides and the ends of the crate, and the extension 8 rests on the end of the crate, the bar 12 firmly holds the top 90 3 in locked condition. At the other end of the top 3, the cross bar or member 9 has its ends overlapping the sides of the crate, as does the member 10, and this cross bar is provided with cut-away or notched corners 95 13 which enable the ends of the slats constituting the top to fit in between the sides and the end of the crate while the ends 14 rest upon the sides of the crate. The hinge members 5 overlap the bar 9 and hold that 100 end of the top 3 secure. In placing the top in position, the bar 9 is first slipped under the members 5 and the ends of the bars 9 and 10 rested upon the sides of the crate, the extension 8 then resting upon the end of 105 the crate. The locking bar 12 is then slipped under one of the members 5 and, while arranged across the extension 8, the other end

100
105

of the bar 12 is sprung under the remaining member 5, thus securely fastening the top in position. The laterally bowed or curved part 6 of the hinge members 5 gives these members greater strength and adaptability to resist outward distortion than if said members had a straight portion connecting the legs 7. By doing entirely away with a catch for holding the top 3, there is no locking device which can be caught or broken, as occurs when a catch is employed. In addition, the ends of the locking bar 12 by their engagement with the hinge members 5, hold said bar securely in position against shifting longitudinally in relation to itself and this bar being adapted to abut the edge of the fixed cleat or bar 10, the lock which is thus provided is secure and has no projecting parts to accidentally cause its disengagement. When the top 3 is removed and the bottom 4 taken out, these parts can be placed within the crate and the latter folded or collapsed, as shown in Fig. 3.

Having thus described my invention, what

I claim as new and desire to secure by Letters Patent, is:-

In a folding crate, sides and ends, hinge members having legs pivotally engaged with the sides and ends and provided with lateral bowed connecting portions for said legs, a bottom held by the lateral bowed portions of the hinge members at the bottom of the crate, a top having cross-pieces adapted to rest on the sides of the crate, said top at one end being engaged by the lateral bowed portions of the hinge members at that end of the crate, the other end of the top being provided with cut-away parts at its corners to receive the bowed portions of the hinge members at that end of the crate and also having an extension adapted to rest upon the end of the crate, and a loose, bodily removable locking bar adapted to rest upon the extension and to have its ends engaged with the bowed portions of the hinge members at that end of the crate.

RUSSELL B. FULLER.
